CLAIM

The ornamental design for a bottle with cap, as shown and described.

DESCRIPTION

FIG. 1 is an exploded perspective top and first side and second side view of a bottle with cap showing my new design;

FIG. 2 is a perspective top and first side and second side view thereof;

FIG. 3 is a perspective bottom and first side and second side view thereof;

FIG. 4 is a first side elevational view thereof;

FIG. 5 is a second side elevational view thereof;

FIG. 6 is a third side elevational view thereof;

FIG. 7 is a fourth side elevational view thereof;

FIG. 8 is a top plan view thereof;

FIG. 9 is a bottom plan view thereof;

FIG. 10 is an exploded perspective top and first side and second side view of a second embodiment of a bottle with cap showing my new design;

FIG. 11 is a perspective top and first side and second side view thereof;

FIG. 12 is a perspective bottom and first side and second side view thereof;

FIG. 13 is a first side elevational view thereof;

FIG. 14 is a second side elevational view thereof;

FIG. 15 is a third side elevational view thereof;

FIG. 16 is a fourth side elevational view thereof;

FIG. 17 is a bottom plan view thereof;

FIG. 18 is a top plan view thereof;

FIG. 19 is an exploded perspective top and first side and second side view of a third embodiment of a bottle with cap showing my new design;

FIG. 20 is a perspective top and first side and second side view thereof;

FIG. 21 is a perspective bottom and first side and second side view thereof;

FIG. 22 is a first side elevational view thereof;

FIG. 23 is a second side elevational view thereof;

FIG. 24 is a third side elevational view thereof;

FIG. 25 is a fourth side elevational view thereof;

FIG. 26 is a top plan view thereof;

FIG. 27 is a bottom plan view thereof;

FIG. 28 is an exploded perspective top and first side and second side view of a fourth embodiment of a bottle with cap showing my new design;

FIG. 29 is a perspective top and first side and second side view thereof;
FIG. 30 is a perspective bottom and first side and second side view thereof;
FIG. 31 is a first side elevational view thereof;
FIG. 32 is a second side elevational view thereof;
FIG. 33 is a third side elevational view thereof;
FIG. 34 is a fourth side elevational view thereof;
FIG. 35 is a top plan view thereof;
FIG. 36 is a bottom plan view thereof;
FIG. 37 is an exploded perspective top and first side and second side view of a fifth embodiment of a bottle with cap showing my new design;
FIG. 38 is a perspective top and first side and second side view thereof;
FIG. 39 is a perspective bottom and first side and second side view thereof;
FIG. 40 is a first side elevational view thereof;
FIG. 41 is a second side elevational view thereof;

FIG. 42 is a third side elevational view thereof;
FIG. 43 is a fourth side elevational view thereof;
FIG. 44 is a top plan view thereof;
FIG. 45 is a bottom plan view thereof;
FIG. 46 is an exploded perspective top and first side and second side view of a sixth embodiment of a bottle with cap showing my new design;
FIG. 47 is a perspective top and first side and second side view thereof;
FIG. 48 is a perspective bottom and first side and second side view thereof;
FIG. 49 is a first side elevational view thereof;
FIG. 50 is a second side elevational view thereof;
FIG. 51 is a third side elevational view thereof;
FIG. 52 is a fourth side elevational view thereof;
FIG. 53 is a top plan view thereof; and,
FIG. 54 is a bottom plan view thereof.
